UNITED STATES PATENT OFFICE.

SAMUEL HERMANN, OF CINCINNATI, OHIO.

TRUNK.

SPECIFICATION forming part of Letters Patent No. 373,456, dated November 22, 1887.

Application filed May 23, 1887. Serial No. 239,081. (No model.)

To all whom it may concern:

Be it known that I, SAMUEL HERMANN, a citizen of the United States, and a resident of Cincinnati, in the county of Hamilton and State of Ohio, have invented certain new and useful Improvements in Trunks, of which the following is a specification.

My invention is an improvement in trunks. Its object is a peculiar arrangement of the trays, by which they may be swung in or out of their normal position, so that the contents of the whole trunk may be reached without lifting out or separating the parts.

The invention will be first fully described in connection with the accompanying drawings, and then particularly referred to and pointed out in the claims.

Referring to the drawings, in which like parts are indicated by similar reference-letters wherever they occur throughout the various views, Figure 1 is a front elevation of a trunk embodying my invention, shown in the open position, with the top trays thrown to one side and the lower tray elevated and resting upon the upper edge of the open cover. Fig. 2 is a central longitudinal section of the open trunk with the trays in normal position, the body of the lower tray being shown in dotted line. Fig. 3 is a detail view taken in transverse section through line $\alpha\alpha$ of Fig. 2, and drawn to about full size, illustrating my preferred means for connecting the movable top trays to the body of the trunk.

The body of the trunk, which is represented by A, with its cover B, are of ordinary construction, and the movable tray C, with its hinged arms c and metal angle-pieces c', which are secured at the top to rest upon the front and back edges of the body and support the tray C, are also well known. These features need not, therefore, be more particularly described.

Upon each end of the body A is an inwardly-projecting ledge, a, which have rabbits upon their inner and upper edges, upon which the arms c rest when the tray C is folded down. The tray C is of a size to drop down between these ledges, the angle-lugs c' resting upon the front and back of the body (which should be recessed in the usual way to receive them) to retain the tray in its lower

position. The top tray or box is divided into two parts, D and E, each of which parts may be partitioned into any desired number of compartments. These parts D and E, when in their normal position, as in Fig. 2, rest upon the edges of the tray C, and also upon the ledges a. The trays D and E are secured to the ledges a by bolts F, the heads of which are countersunk into the bottom of the boxes from the upper side, and concealed from view when the trunk is finished by a covering, g. The bottom of the box E has a longitudinal groove or slot, e, nearly its entire length, through which the bolt F passes, so that it may slide from over the tray C, as seen in Fig. 2. The opposite bolt F passes through a hole in the bottom of box D and serves as a pivot upon which the box D turns to uncover the tray C, as in Fig. 1, and cover it, as in Fig. 2. When the box D is swung to its place, as in Fig. 2, and the box E pushed in against it, the two parts are held together by a hook, h, on one part catching with a staple or screw-eye secured in the other part. It will thus be seen that when it is desired to reach the contents of tray C the parts are unhooked or disconnected, the part E drawn out, as in Fig. 1, and the part D swung around upon its pivot, as seen in the same view. To reach the trunk-body, the tray C is lifted up, its rear side being supported upon the front edge of the open cover B, while its front side is supported by the arms c.

I have shown in the drawings my improvement applied to trunks in which the trays are lifted to uncover the body; but it is equally applicable to those in which the tray and upper boxes are hinged or arranged to fold back into the top of the open cover to uncover the body of the trunk. In this latter case the tray C is the full length of the trunk and has ledges, as a, upon each end, through which the bolts F are passed to secure the boxes, in the same manner as shown.

I have shown the boxes and ledges connected by screw-bolts; but it is evident that any well-known guide or pivot connection may be employed for uniting the parts—as, for instance, a plain wood-screw or ordinary rivet.

What I claim is—

1. In a trunk-tray, the combination, substantially as specified, of the inwardly-projecting ledges *a*, the adjustable boxes D E, mounted thereon and moving in horizontal planes, and bolts F, for adjustably securing the boxes to the ledges, for the purpose set forth.

2. In a trunk, the combination of the body A, having ledges *a*, the tray C, and boxes D E, moving in horizontal planes, with the bolts F,

for retaining the boxes to the ledges, one of said boxes being adapted to slide upon its retaining-bolt, while the other is adapted to swing upon its bolt as a pivot, substantially as shown and described.

SAMUEL HERMANN.
